(57) **CLAIM**

The ornamental design for an audio dock for a tablet computer, as shown and described.

DESCRIPTION

FIG. 1 is a front and left side perspective view of an audio dock for a tablet computer showing our new design;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is a front and left side perspective view thereof wherein the tablet computer is shown in broken lines and seated in the cradle of the audio dock.

The elements depicted in broken lines in the figures are included for environmental purposes only and from no part of the claimed design.
